UNITED STATES PATENT OFFICE.

GEORGE ARNOLD FROST, OF SOUND BEACH, CONNECTICUT.

TONE-REGULATOR.

1,307,664.

Specification of Letters Patent. Patented June 24, 1919.

Application filed August 6, 1918. Serial No. 248,591.

To all whom it may concern:

Be it known that I, GEORGE ARNOLD FROST, a citizen of the United States, residing at Sound Beach, in the county of Fairfield and

5 State of Connecticut, have invented certain new and useful Improvements in Tone-Regulators, of which the following is a specification.

This invention relates to talking machines 10 and as its primary object, contemplates the provision of means for regulating or restricting the vibrations of the reproducing diaphragm, to modify the volume of the sound reproduced and to eliminate harsh 15 and discordant notes therefrom.

A still further object of the invention is to so construct the vibration regulating or dampening device that the same may be in the form of an attachment which can be 20 conveniently attached to the sound box of practically any type of talking machine.

A still further object of the invention resides in the provision of an adjustable damper which can be readily moved into engagement with the reproducing diaphragm 25 during the operation of the talking machine, to modify the sound being reproduced without danger of causing stoppage of the machine.

30 Other objects of the invention as well as the specific construction and arrangement of the various elements thereof will be more readily understood from the following description and accompanying drawings, in 35 which:—

Figure 1 is a front elevation of a sound box having my invention applied thereto.

Fig. 2 is a vertical sectional view of the device in applied position, and

40 Fig. 3 is a fragmentary plan view of the body portion or clamping plate.

In the present drawings I have shown certain elements of a talking machine, such as the sound box 1, the reproducing diaphragm 2, and the stylus arm 3. These parts, as 45 will be readily recognized from the drawings, are all of conventional form and have no relation to the present invention other than to show the application thereof.

50 The dampening or regulating device is preferably in the form of a removable attachment and to this end consists of a suitable body portion or clamping plate 4 having the opposite ends thereof bent at right angles to provide clamping arms 5 and 6

for engagement with opposite edge portions of the sound box substantially as shown in Fig. 2. One of these clamping arms is extended as indicated at 7 to provide a finger piece to facilitate removal of the clamp. 60 Intermediate the arms 5 and 6 the center portion of the clamping plate is directed outwardly to provide a bridge member 8 from the outer face of which extends an externally threaded collar 9. This collar 9 65 surrounds the opening 10 formed in the clamping plate for the reception of the sliding damper member 11. This damper 11 is substantially cylindrical in cross section and is equipped at its inner end with an outwardly directed flange 12 which is engageable with the diaphragm 2 and for this reason is provided with a covering pad 13 of any suitable material, such as chamois, or the like. The outer end of this damper 11 70 is also equipped with an outwardly directed flange 14 provided with one or more radial projections 15 fitting into suitable grooves 16 formed in the collar 9 to prevent rotary movement of the damper. A coil spring 17 75 confined beneath the collar 14 and the adjacent face of the plate 4 normally serves to retain the damper 11 out of engagement with the diaphragm 2.

A screw cap 18 is threaded upon the collar 80 9 and is adapted to engage the flange 14 of the damper to force this flange inwardly against the tension of the spring 17 thus bringing the inner flanged end of the damper into engagement with the diaphragm 2 90 to regulate or lessen the vibrations of the diaphragm, thus decreasing the volume of the sound reproduced and eliminating harsh and discordant notes therefrom.

The foregoing description and accompanying drawings have reference to what might be considered to be the preferred or approved form of my invention. I desire it to be understood that I may make such changes in construction, combination 95 and arrangement of parts, materials, dimensions, et cetera, as may prove expedient and fall within the scope of the appended claims.

Having thus fully described my invention what I claim as new and desire to secure by 105 Letters Patent, is:—

1. A device of the character described comprising a clamping plate, a slidable damper carried by said plate, a spring engaging said plate and bearing upon said damper for 110

urging the damper in one direction, and means for limiting the movement of said damper in such direction.

2. A device of the character described comprising a supporting plate, having a collar thereon, a slideable damper passing through said plate, a spring bearing upon said plate and engaging the damper for forcing the damper in one direction, and a cap fitting over the outer end of said damper and connected to said collar for limiting the movement of said damper in one direction.

3. A device of the character described comprising a supporting plate having an opening, a collar carried by said plate adjacent said opening, a damper extending through said opening a flange formed on the outer end of said damper, a coiled spring surrounding said damper and bearing upon said plate and upon said flange for forcing said damper outwardly, said collar having grooves upon the inner surface thereof, radial projections formed on said flange and fitting within said grooves, thus holding the damper against rotation, and a cap fitting over said damper and being screwed into engagement with said collar, thus limiting the damper against outward movement and also regulating the normal extent of inward movement of the damper, although the damper is yieldably supported by said spring.

4. A device of the character described comprising a clamping plate, a slideable damper carried by said plate, a spring carried by said damper and engaging said plate for forcing the damper in one direction, and adjustable means for limiting the movement of said damper in such direction.

5. A device of the character described comprising a clamping plate, a slideable damper carried by said plate, a spring engaging said plate and bearing upon said damper for forcing the damper in one direction, and an adjustable cap connected to said plate for limiting the movement of said damper in such direction.

6. A device of the character described comprising a supporting plate having a collar thereon, a slideable damper passing through said plate, a spring bearing upon said plate and engaging the damper for forcing the damper in one direction, and means adjustably connected to the collar and fitting over the outer end of said damper for limiting the movement of said damper in one direction.

7. A device of the character described comprising a supporting plate having an

opening, a collar carried by said plate adjacent said opening, a damper extending through said opening, a flange formed on the outer end of said damper, and a coil spring surrounding said damper and bearing upon said plate and upon said flange for forcing said damper outwardly, said collar having grooves upon the inner surface thereof, radial projections formed on said flange and fitting within said grooves, thus holding the damper against rotation, and adjustable means fitting over said damper and engaging said collar, thus limiting the outward movement of the damper, and also regulating the normal extent of inward movement of the damper although the damper is yieldably supported by said spring.

8. A device of the character described comprising a supporting plate having an opening, a collar carried by said plate adjacent said opening, a damper extending through said opening, a flange formed on the outer end of said damper, a coiled spring surrounding said damper and bearing upon said plate and upon said flange for forcing said damper outwardly, means for holding said damper against rotation within said collar, and a cap fitting over said damper and being screwed into engagement with said collar, thus limiting the outward movement of the damper and also regulating the inward movement of the damper although the damper is yieldingly supported by said spring.

9. A device of the character described comprising a supporting plate having an opening, a collar carried by said plate adjacent said opening, a damper being slidably mounted through said opening, a flange formed on the outer end of said damper, a coiled spring surrounding said opening and bearing upon said plate and upon said flange for forcing said damper outwardly, means for holding said damper against rotation within said collar and means adjustably connected to said collar and engaging said damper for limiting the outward movement of the damper and also regulating the normal extent of inward movement thereof, although the damper is yieldably supported by said frame.

In testimony whereof I affix my signature in presence of two witnesses.

GEORGE ARNOLD FROST.
